UNITED STATES PATENT OFFICE

148,512

DESIGN FOR A DEFLECTOR FOR INFANT'S TOILET SEAT

Samuel George Zuckerman, New York, N. Y.

Application May 11, 1946, Serial No. 129,591

Term of patent 14 years

(Cl. D4—5)

To all whom it may concern:

Be it known that I, Samuel George Zuckerman, a citizen of the United States, resident of the city of New York, in the county of Kings, State of New York, have invented a new, original, and ornamental Design for a Deflector for Infant's Toilet Seat, of which the following is a specification, reference being had to the accompanying drawing, forming part thereof.

In the drawing,

I claim:

The ornamental design for a deflector for infant's toilet seat, substantially as shown.

SAMUEL GEORGE ZUCKERMAN.
